UNITED STATES PATENT OFFICE.

LOUIS N. D. WILLIAMS, OF OGONTZ, PENNSYLVANIA.

STITCH TRANSFERRING AND DOUBLING DEVICE.

1,089,174.

Specification of Letters Patent.

Patented Mar. 8, 1914.

Application filed August 8, 1913. Serial No. 763,297.

To all whom it may concern:

Be it known that I, Louis N. D. WILLIAMS, a citizen of the United States, residing in Ogontz, Montgomery county, Pennsylvania, have invented certain Improvements in Stitch Transferring and Doubling Devices, of which the following is a specification.

My invention consists of certain improvements in the stitch transferring device for which Letters Patent No. 1,068,853, dated July 29, 1913, were granted to Walter D. Butz and myself as assignees of said Walter D. Butz, the objects of my invention being to reduce the cost of said device, to facilitate the operation of the same, and to increase its stability. These objects I attain in the manner hereinafter set forth, reference being had to the accompanying drawings, in which—

Figure 1 is a transverse section of said stitch transferring device made in accordance with my invention and illustrating the parts in position to receive the knitted web from the needles; Fig. 2 is a similar view illustrating the parts adjusted to the position for transferring the stitches from one-half of the transfer quills to the other half of the same, and Fig. 3 is a side elevation of the device with the parts in the position illustrated in Fig. 2.

The device shown and described in the above noted patent, when intended for use in connection with a circular knitting machine, consisted of a split ring having, on each half of the ring, longitudinally projecting points or quills hereinafter, for convenience, termed "quills" which, when the halves of the ring were in the position shown in Fig. 1 of the accompanying drawings, that is to say with all of the quills pointing in the same direction, received the stitches from the needles of the knitting machine, the two halves of the ring being then adjusted in respect to one another so as to cause the quills of one half to register with and point toward the quills of the other half in order that the stitches carried by one set of quills could be readily transferred to the quills of the other set, whereby the doubled stitches then carried by said latter quills might be united as by a separate course of stitches, or mechanically transferred from the quills to the points of a looping machine for uniting them, the object of the invention being to dispense with

the manual application of the stitches to the looper points which is now resorted to in uniting the stitches around one half of a knitted web to those around the other half of the same, as for instance in closing the toe of a stocking, this manual application of the stitches being a tedious and expensive one and requiring the employment of a highly skilled class of labor.

In the accompanying drawings 3—3^a represent the opposite halves of a split ring, each half being composed of two members 58—59 or 58^a—59^a, which are bolted together and confine between them the shanks 70 of a semi-circular series of quills 10 or 10^a, these quills projecting longitudinally beyond the members 58—58^a of the ring so as to be applied to the needles of the knitting machine from which the stitches are to be transferred, the parts occupying the position shown in Fig. 1 during the application of the transferring device to the needles of the knitting machine and the transfer of the stitches from the needles to the quills, 80 but being adjusted to the position shown in Fig. 2 when the stitches upon one set of quills are to be transferred to the quills of the other set. In order to facilitate this adjustment of one half of the ring in respect to the other it is preferable to hinge the halves of the ring to one another, and in order that each quill on one-half of the ring may properly register with its corresponding quill on the other half the axis of 85 the hinge must be in line with the points of the quills and with the plane of division between the halves of the ring.

In the patented device the hinge structures were on the outside of the ring and in order 95 that they would not interfere with the application of the quills to the needles of the knitting machine it was necessary to retract them from their normal or operative position during the time that the stitches were 100 being transferred from the needles to the quills and to afterward adjust them to their normal or operative position when the transfer device had been removed from the needles of the knitting machine. In order to 105 overcome this objection I use stationary hinges on the inside of the ring, these hinges being located so far inwardly beyond the transfer quills 10—10^a as not to interfere with the needle cylinder or with the web 110 thereon when the quills are applied to the needles, and each hinge structure consisting

of a member 55 secured by appropriate means, such as a screw 56, to the half 3 of the ring and a member 55^a secured by a screw 56^a to the half 3^a of the ring, as shown 5 in Fig. 3.

In order to strip the stitches from either set of quills and transfer them to the other set when the parts of the transfer device are in the position shown in Figs. 2 and 3 I provide a two-part stripping disk 25—25^a provided with fingers 26—26^a projecting between the quills 10—10^a, this disk being carried by a two-part cylinder 24—24^a which fits within the quill-carrying ring, each 15 member of the cylinder being slotted longitudinally as at 19—19^a for the reception of the screw 20—20^a whereby it is held in position upon its corresponding half of the ring while at the same time sufficient longitudinal movement is permitted to cause the 20 fingers to strip the stitches from the quills of either set and transfer said stitches to the quills of the other set.

The hinge members instead of being applied to the ring segments may, if desired, be mounted upon the segments of the stripper but in such case the hinge members will have to be separable from one another in order to permit movement of one stripper 30 segment independently of the other in trans-

ferring the stitches from one set of quills to the other.

I claim:

1. The combination, in a stitch-transferring device, of a circular series of stitch receiving quills, a two-part carrier therefor, and a hinge connection located within the circle of quills whereby it may occupy an operative relation to the quills while the latter are being applied to the needles of the 35 knitting machine.

2. The combination, in a stitch-transferring device, of a circular series of stitch-receiving quills, a two-part carrier therefor, and a hinge fixedly located in operative position within the circle of quills. 40

3. The combination, in a stitch-transferring device, of a circular series of stitch receiving quills, a two-part carrier therefor, and a hinge connection fixedly attached to 45 the parts of said carrier within the circle of quills.

In testimony whereof, I have signed my name to this specification, in the presence of two subscribing witnesses.

LOUIS N. D. WILLIAMS.
